J. F. AMEND.
WINDMILL TOY.
APPLICATION FILED APR. 10, 1918.

Patented July 30, 1918.

UNITED STATES PATENT OFFICE.

JUDSON F. AMEND, OF PORTLAND, OREGON.

WINDMILL TOY.

1,274,132.

Specification of Letters Patent. Patented July 30, 1918.

Application filed April 10, 1918. Serial No. 227,721.

To all whom it may concern:

Be it known that I, JUDSON F. AMEND, a citizen of the United States, residing at Portland, in the county of Multnomah and 5 State of Oregon, have invented new and useful Improvements in Windmill Toys, of which the following is a specification.

This invention relates to movable figure toys and, more particularly, to such toys 10 which are actuated by air pressure and which may be called "windmill toys."

It consists in a frame adapted to be mounted in an exposed position on a building, a flag pole, or the like, and provided with 15 a vane or rudder which keeps it facing the wind. A fan wheel is carried by the frame on the opposite side from the rudder and has a friction roller adjustably mounted on its shaft. The upper part of the frame 20 constitutes a platform for the toy figures to travel on and has a central bearing for the stem or shaft of a friction disk, which rests upon and is driven by said friction roller. The toy figures, which may represent bi- 25 cycle riders, are connected to said stem or shaft by radial arms, which are pivoted or otherwise loosely connected to the upper part of said stem or shaft, so that the figures will rest by their own weight on said plat- 30 form, and the friction disk will bear by gravity on the roller. When the fan wheel is rotated by the wind, the figures are caused to travel around on the platform, simulating a bicycle race in the embodiment illustrated. 35 The rudder is preferably painted to represent the United States flag, and the fan wheel may be similarly painted. The speed at which the figures travel may be varied by adjusting the friction roller longitudinally 40 of the fan wheel shaft. The device forms an amusing toy for children and an attractive ornament as a weather vane.

I will now describe it in detail with reference to the accompanying drawing, in 45 which:

Figure 1 is an elevation of the toy mounted on a flag pole or post.

Fig. 2 is a plan view of the same.

Fig. 3 is a vertical section through the 50 upper part of the frame.

Fig. 4 is a top view of a modified form of connection between the radial arms and the friction disk shaft.

Fig. 5 is a side view, partly in section, of 55 another modified form of said connection.

Fig. 6 is a detail plan view of the form of connection shown in Figs. 1 and 2.

In these views, 1 represents the frame, preferably constructed of wood, and 2 the rudder or vane, which is preferably of metal 60 and painted, as stated, to represent the flag. 3 is the platform at the top of the frame, and 4 the pin by which the frame is revolu- 65 bly mounted on the post 5.

6 is the fan wheel carried by the shaft 8, 65 journaled in the upright members 7 of the frame, as shown in Fig. 3. Shaft 8 carries the friction roller 9, which is adjustable longitudinally thereon. As shown, the roller is provided with a set-screw 10 to hold it in 70 adjusted position, but the roller may have a screw-threaded connection with the shaft, if preferred. The platform 3 has a central bearing sleeve for the stem or shaft 11 of the friction disk 15, which rests upon and 75 is driven by the roller 9. In the form shown in Figs. 1, 2, 3 and 6, the upper part of the stem 11 is flattened and engages elongated slots in the ends of the arms 12, a pin 13 passing through the top of the stem 80 to hold the arms in place. The outer ends of said arms carry the toy figures 14 which, as shown, are mounted on bicycles with their feet connected to cranks so as to simulate pedaling. As before stated, it is necessary that the radial arms carrying the figures be loosely connected to the stem or shaft, so that the weight of the figures will keep them in contact with the platform and so that the friction disk will bear on the roller. 85 In Fig. 5, the arms are rods 22, which pass through slots in the stem and are provided with nuts 24 on each side of the stem. A modified form of connection is shown in Fig. 4, in which the stem carries a collar 23, to 90 which the arms 25, in this case shown as three in number, are pivoted.

In small sizes of the toy, I prefer to use only two of the toy figures, but of course 100 three or more can be used in larger sizes.

Having described my invention, what I 105 claim is:

1. A top comprising a frame provided with a rudder and mounted so that it can turn in the wind, a platform on the upper 105 part of said frame, a shaft projecting upwardly through said platform, a radial arm loosely mounted at one end on said shaft, a toy figure attached to the other end of said arm, a fan wheel rotatably mounted on said 110

frame, and connections between said wheel and said shaft.

2. In a windmill toy, a frame, a platform thereon, a shaft projecting therethrough, a 5 fan wheel carried by said frame, connections from said wheel to drive said shaft, a toy figure resting on said platform, and a radial arm rigidly connected at one end to said figure and loosely connected at the other 10 end to said shaft.

3. A windmill toy comprising a fan, a stationary platform below which the shaft of said fan is journaled, a driving member on said shaft, a driven member journaled in 15 said platform, and toy figures arranged to travel on said platform and having a loose connection to said driven member.

4. A windmill toy comprising a frame having a rudder or vane, means to revolvably 20 support said frame, a fan wheel on said frame, a shaft for said wheel journaled in said frame, a friction roller on said shaft, a platform on said frame, a friction disk resting on said roller, a shaft or stem carried 25 by said disk and journaled in said

platform, toy figures adapted to travel on said platform, arms attached to said figures and pivoted to said shaft or stem, and means whereby said roller can be longitudinally adjusted on said fan shaft.

5. A toy of the class described, comprising a frame having a vane or rudder projecting therefrom and supported so as to be capable of turning on a vertical axis, a horizontal shaft journaled in said frame, a fan wheel on one end of said shaft, a friction roller on said shaft within said frame, a friction disk resting on said roller, a platform on said frame above said disk, a stem carried by said disk and journaled in said platform, radial arms carried by said stem above said platform and so as to be capable of having a limited vertical swinging movement thereon, and a wheeled toy figure secured to the outer end of each arm so as to travel around 40 on said platform when said fan wheel rotates.

In testimony whereof I have hereunto set my hand.

JUDSON F. AMEND.
